(57) **CLAIM**

The ornamental design for a straight latch cam as shown and described.

DESCRIPTION

FIG. 1 is a first perspective view of a straight latch cam; FIG. 2 is a top view of the straight latch cam of FIG. 1; FIG. 3 is a bottom view of the straight latch cam of FIG. 1; FIG. 4 is a front side view of the straight latch cam of FIG. 1;

FIG. 5 is a rear side view of the straight latch cam of FIG. 1;

FIG. 6 is a first side view of the straight latch cam of FIG. 1; and,

FIG. 7 a second side view of the straight latch cam of FIG. 1.

Any components in the appended drawings shown in broken lines are for illustrative purposes only and form no part of the claimed design.

1 Claim, 3 Drawing Sheets
